UNITED STATES PATENT OFFICE.

WILLIAM B. TREADWELL, OF ALBANY, NEW YORK.

SUPPLY-CYLINDER COAL-STOVE.

Specification forming part of Letters Patent No. 44,900, dated November 1, 1864.

To all whom it may concern:

Be it known that I, WILLIAM B. TREADWELL, of the city and county of Albany, State of New York, have invented a new and Improved Supply-Cylinder Coal-Stove; and I do hereby declare that the following is a full, clear, and exact description thereof, reference being had to the accompanying drawings, making a part of this specification, in which—

Figures 1 and 2 represent diametrical sections through my improved stove, taken in planes at right angles to each other. Figs. 3 and 4 show two forms of a valve which I employ in my stove. Fig. 5 is a horizontal view of the base of the stove, reduced scale. Fig. 6 is a horizontal view of the stove, taken at the point indicated by red line *x x*, Fig. 1. Fig. 7 is a perspective view of the fire pot. Fig. 8 is a perspective view of the fire-brick. Fig. 9 is a horizontal view of the feed cylinder section of the stove taken at the point indicated by red line *y y*, Fig. 2. Fig. 10 is a vertical section of flues for conducting warm air into upper rooms, which may be applied to my stove, if desired.

Similar letters of reference indicate corresponding parts in the several figures of both sheets.

This invention relates, chiefly, to improvements on the supply-cylinder coal-stove for which Letters Patent were granted to me September 29, 1863.

The object of my invention is to provide for a general distribution of heat throughout every part of a base-burning stove, and at the same time to prevent the escape of gas into the room—that is to say, I desire to have an ascending and also a descending circulation of heat through the stove, so as to heat the upper part as well as the lower part thereof, as will be hereinafter described.

Another object of my invention is to so construct the fire pot of a base-burner that ashes, &c., shall not collect near the mica door nor obstruct the flues passing off from said fire-pot, as will be hereinafter described.

Another object of my invention is to so construct the fire-brick surmounting the fire-pot that those portions which constitute the arches over the flues shall cause the descending coals to fall toward the center of the fire-pot, and thus keep the flue-openings clear, as will be hereinafter described.

Another object of my invention is to so construct a supply-cylinder coal-stove that while the cylinder is brought down closely to the

fire-brick lining and the latter is mounted upon the fire-pot means shall be provided for the ascension as well as descension of the products of combustion in their passage from the fire to the common exit flue, all as will be hereinafter described.

To enable others skilled in the art to make and use my invention, I will describe its construction and operation.

In the accompanying drawings, Figs. 1, 2, and 5, *A* represents the base of the stove, within which are chambers or flues *M M M*, formed by partitions or deflecting-plates *a a*.

B is the ash-pit section of the stove, within which are two chambers, *K*, that are formed by means of two plates, *j j*, passing across from the front to the back of the stove, and attached to the upper plate of said section is the grate. (Shown in Figs. 1 and 2 directly under the fire-pot.)

C, Figs. 1, 2, and 7, represents the fire-pot, which has its inner surface ribbed, for the purpose of protecting it from the intense heat to which it is subjected, and also giving it greater strength and durability. Said ribs serve to keep the coals away from the inner surface of the fire-pot, and thus to form a space between this surface and the coals. This fire-pot *C* has a lipped projection, *b*, Fig. 2, extending outward to the outer casing of the stove in front, to prevent ashes collecting opposite to the mica door. Otherwise coals and ashes would obscure the light. The fire-pot *C* has also lipped projections *c c*, Figs. 1 and 7, extending laterally outward, which unite with the descending flues *F F* at the sides or ends of the stove, and, formed thus, coals and ashes will not obstruct the flues.

D, Figs. 2, 6, and 8, are fire-brick, which have their bearings upon the plate at the top of the fire-pot *C*—the plate which caps the fire-pot section of the stove. Said brick are made in sections, and those sections which form the jambs *d d d*, Figs. 6 and 8, to the flues have shoulders formed on them to receive the brick *h h*; Fig. 1, which latter cap and cover the flues. Said fire-caps *h h* are made so as to incline the coals in descending, especially those immediately over the flues, more inward or more toward the center of the fire-pot, and thus prevent them falling into and choking the flues. The brick *P*, Figs. 2 and 8, is held in its proper position by jambs *m m*; Fig. 6, best made of cast-iron, placed at the sides of said opening, which is inclosed by a door holding the mica light. Passing later-

ally through the said fire-brick D are two flues, *e e*, Figs. 1 and 6, which connect with the descending flues *F F*, and also with the descending flues *K K*, and also with the descending flues *o o*, which flues surround the feed cylinder, as shown in Figs. 1, 2, and 9, and has its outlet through valve *G*, hereinafter described.

E, Figs. 1, 2, and 9, represent the feed-cylinder, the base of which is held in position independently of the fire-brick at bearings *i i*, formed upon the inner surface of the outer casing of the stove, as shown in Fig. 2.

ff, Fig. 1, are the inner end plates of the upper section of the stove, the upper parts of which are lipped or made so as to recede inward.

In Fig. 1, *g g* are perforated plates for the admission of cold air. These plates are outside of the plates *ff*, as represented in the figure just referred to.

H H is a ring, of elliptical form, which caps the upper section of the stove, and rests upon the upper edges of plates *ff* and *g g*.

L L, Figs. 1 and 9, are two cold-air flues at the ends of the stove, which, starting from immediately underneath the ring *H*, pass upward through the flues *o o*, so that the products of combustion in passing upward completely surround them. Thus the air is heated in ascending through the flues *L L*.

By connecting the pipes represented in Fig. 10, Sheet 2, with the upper ends of the flues *L L*, warm air can be conducted into apartments in the upper part of the building.

In Figs. 2, 3, and 4, Sheet 1, *G* represents a perforated valve, which regulates the operation of the stove. The office of this valve is to divide and distribute equally and continually the products of combustion, so that every part of the stove can be heated at the same time, and so as to carry off into the flue behind at all times during the operation of the stove all accumulations of gas. Two very desirable objects are thus obtained, and they are not obtained in any other stove.

In all supply-cylinder coal-stoves where the products of combustion are carried downward into the base of the stove more or less of the gases will escape through unavoidable openings into the room.

A valve constructed upon the principle shown in Figs. 2, 3, and 4 will entirely overcome the objection, and the operation will be as follows: The products of combustion rise within the fire-pot *c* to its top and pass out through the openings *e e* through the fire-brick lining *D* and openings *c c*, formed by the lipped projections of the fire-pot, into descending-flues *F F*, as shown in Fig. 1. Passing thence downward through chambers *K*, they are distributed by means of partition plates *a a* through the base of the stove, whence they pass off into flue *J* behind. At the same time, and while the products of combustion are descending into and being distributed through the base of the stove *A* and

escaping through flue *J*, as described, a portion of them, together with the gases, are passing upward and escaping slowly through the central opening in valve *G* into the common flue *J*. Thus we have a descending draft and at the same time a gentle ascending draft, as indicated by the direction of the arrows in Fig. 1. Cold air, after passing through the perforated walls *g g*, is drawn closely to the heated plates *f f*, and when the air is partially heated it rises rapidly through the flues *L L*, which are heated by the products of combustion passing around them while passing upward through the flue *O*, and thence, the air being thus heated, it enters pipes, which may be connected with the top of the stove leading into a room above, as described above.

The valve *G*, which I have represented in Fig. 4, has central slotted openings through it, and a slide, which can be used to regulate the size of said openings according to the amount of upward draft required.

I do not limit my invention to the use of a valve constructed like that represented in Fig. 3, nor like that shown in Fig. 4, as a variety of forms may be employed to obtain the result herein set forth.

In regard to the ascending flues *L L* and the branch connection represented on a small scale in Fig. 10, I will state that when it is not desired to warm other apartments than that in which the stove is arranged these parts may be dispensed with.

Having thus described my invention, what I claim as new, and desire to secure by Letters Patent, is—

1. A supply-cylinder coal-stove or base-burner which is constructed with ascending flues passing through the upper portion of the stove, and descending flues passing down through the lower portion of the stove, in conjunction with an appliance which shall admit of the escape of gas from the upper section of the stove into the exit-flue, substantially as described.
2. The application of a perforated valve or damper, *G*, or its equivalent, to a base-burner having ascending and descending flues, substantially in the manner described.
3. Constructing the fire-pot *C* with a lipped projection or projections, substantially as and for the purposes set forth.
4. So constructing the fire-brick lining that those portions thereof which cover the arched openings through this lining shall serve to protect said openings from filling up with coal, substantially as described.
5. The combination of a lipped fire-pot constructed, substantially as described, with fire-brick lining having arched openings or flues through it, substantially as described.
